UNITED STATES PATENT OFFICE.

WILLIAM WRIGHT, OF CHICAGO, ILLINOIS, ASSIGNOR TO FREDERICK A. LESTER, OF CHICAGO, ILLINOIS.

DRAFT-GEAR YOKE.

1,291,338.

Specification of Letters Patent. Patented Jan. 14, 1919.

Application filed May 28, 1915. Serial No. 30,989.

To all whom it may concern:

Be it known that I, WILLIAM WRIGHT, a citizen of the United States, residing at Chicago, in the county of Cook and State of Illinois, have invented certain new and useful Improvements in Draft-Gear Yokes, of which the following is a specification.

This invention relates to improvements in draft gear yokes, and has for its object to 10 provide a device of that nature in which the yoke is provided with an open-hooded forward end constructed to permit the ready insertion thereinto of a coupler butt.

Still another object is to provide in conjunction with the structure of the type described above, means to lock the coupler against removal from the yoke, such means being arranged to permit ready and quick assembling of the structure, as well as easy dis- 20 assembling.

Still another object is to provide a device which will permit of the coupler being removed from the car, or applied thereto, without disturbing the draft gear, or the 25 yoke, or in other words, without their having to be also removed, in either case.

Still another object is to provide a device which can be applied to cars in service without any change in the construction of the 30 car, or its parts.

These and other objects I accomplish by means of the structure set forth and described in the following specification and shown in the accompanying drawings, in 35 which:—

Figure 1 is a vertical longitudinal section through one form of my device showing the coupler butt in elevation;

Fig. 2 is a horizontal section through the 40 yoke showing the coupler butt and draft rigging removed;

Fig. 3 is an end elevation of the locking block;

Fig. 4 is a side elevation, partially in sec- 45 tion, of a modified form of yoke;

Fig. 5 is a vertical transverse section of the same;

Fig. 6 is a view similar to Figs. 1 and 4 of still another form of my invention; and

50 Fig. 7 is a vertical transverse section through the same.

Like numerals refer to like elements throughout the drawings, in which 10 designates generally my yoke member comprising the strap portions 10^a, 10^b united at their

rear extremities by the rear wall 10^c. At its forward end the strap 10^b is formed with a downturned shoulder or lug 10^d. The lower strap 10^a at its forward portion is depressed or offset, as indicated by numeral 10^e, this 60 offset portion being apertured, as indicated by numeral 10^f. I have shown one form of draft rigging in Fig. 1, mounted in the yoke 10, the same being of well known construction and comprising front and back follower 65 plates 11 and 12, respectively, between which is mounted the spring 13. 14 designates a coupler shank terminating in a butt 14^a, having the rear shoulders 14^b. The yoke 10 is constructed with the sides or wings 10^g ex- 70 tends between and formed integral with the straps 10^a and 10^b, as shown in Fig. 1, this construction forming a hooded forward end, as will be apparent.

The yoke is constructed with its forward 75 end of such size that the coupler butt 14^a may be readily inserted therein, and one of the shoulders 14^b will engage a shoulder 10^d of strap 10^b when in proper assembled relation. To maintain the coupler butt in such relation, and to further prevent its withdrawal 80 from the yoke, I provide what I term a locking block 16 having the bearing surface 16^a, at one end of which is located the upwardly projecting shoulder 16^b arranged to coact 85 with the corresponding shoulder 14^b of the coupler butt 14^a. This locking block 16 is further provided with the outwardly-projecting or shoulder portion 16^c on its front face, the same being intended to abut against 90 the front wall of aperture 10^f and strap portion 10^e. Below the shoulder portion 16^c of block 16 extends downwardly the front 95 wall 16^d of block 16, the same being provided with a groove or recess 16^e therein. This front wall 16^d is provided with a bolting aperture 16^f therethrough leading from the grooves 16^e; see Figs. 1 and 3. The strap portion 10^e is provided with the downwardly-projecting shoulder or flange 10^g, 100 grooved as indicated by numeral 10^h, this groove being similar in size and arrangement to the groove 16^e in the front face of locking block 16 which abuts against the rear of shoulder 10^g, as shown in Fig. 1. 105 The shoulder or wall 10^g is also provided with an aperture arranged to aline with aperture 16^f, and a bolt or similar member 17 extends through such apertures, being secured in place by the nuts 17^a threaded there-

on. The locking block 16 is constructed with a transverse strengthening rib 16^k. The block 16 is arranged so that bearing surface 16^a will aline or lie slightly above the plane 5 of the upper surface of strap 10^a, so that under extreme buffing strains the coupler butt 14^a will ride over upon the strap 10^a, as will be apparent. Another advantage of 10 this construction resides in the fact that by the elimination of the ordinary form of transverse key projecting on either side of the yoke, I am enabled to mount the draft rigging at a place of less width than is ordinarily needed.

15 In Figs. 4 and 5 I have shown a modification of the structure described above. In this form of my device I construct the yoke strap 10^a with a pair of depending flanges 10^m projecting downwardly from the portion 10^e, and slotted or apertured as indicated by numerals 10ⁿ. A locking block 20 fits in the aperture 10^f; this locking block, as in the case of block 16 described above; has the bearing surface 20^a, at one end of 20 which is provided the upwardly extending shoulder 20^b. This locking block 20 is provided with the longitudinal groove 20^d at its underside, as shown for example in Fig. 5, and a tapered key 21 is driven through apertures 10^m, and through the slot 20^d, serving to prevent displacement of the locking block 20 when the structure is assembled. A cross key or pin 22 may be driven through an aperture 21^a adjacent one end of the key 21 25 and forwardly of the forward flange 10^m, as shown in Fig. 4. The operation and arrangement of the structure shown in Figs. 4 and 5 is similar to that of the structure shown in Figs. 1 and 3, and needs no further description herein.

30 In Figs. 6 and 7 I have shown still another modification in which the portion 10^e of strap 10^a is provided with the aperture 10^f. Projecting outwardly from the strap 45 portions 10^e are the side flanges 10^e, provided with bolting apertures 10^p and reinforced by transverse ribs 10^r, see Fig. 7. A locking block 30 is provided having outwardly-directed flanges 30^a arranged to lie below 50 flanges 10^e, and provided with bolting apertures 30^b alining with apertures 10^p for insertion therethrough of the locking bolts 31 carrying the nuts 32 threaded thereon, as shown in Fig. 7. The central portion of 55 the locking block 30 extends upwardly into the hooded end of the yoke and is provided with the flat bearing surface 30^c, terminating at one end in the upwardly extending shoulder 30^d. This bearing surface 30^c is 60 substantially in alinement with the upper surface of yoke strap 10^a, and the operation and functioning of this structure is similar to that shown and described in connection with the other forms.

65 While I have shown and described several

embodiments of my invention, it is obvious that it is susceptible of other modifications, such as arranging the key 21 laterally instead of parallel with the center line of the yoke, as has been shown in Fig. 4, or the 70 substitution of pins or bolts in lieu of the key,—or the substitution of a key for the bolt in Fig. 1,—in either case, so that I do not wish to be restricted to the form shown or described beyond the scope of the 75 appended claims.

What I claim is:

1. A yoke having a hooded forward end constructed to permit insertion therein of a coupler butt, said hooded end being formed 80 with an engaging lip and an aperture, a locking member attached to said yoke and projecting through said aperture, said locking member being provided with a shoulder coacting with said lip to prevent removal 85 of a coupler butt from said yoke, said hooded end of said yoke being provided with a projecting flange, and means to attach said locking member to said flange.

2. A yoke having a hooded forward end 90 constructed to permit insertion therein of a coupler butt, said hooded end being formed with an engaging lip and an aperture in the horizontal wall thereof opposite said lip, a locking member attached to said yoke insertible and removable upwardly through 95 said aperture, said locking member being provided with means coacting with said lip to prevent removal of a coupler butt from said yoke, said locking member being further provided with a bearing surface for 100 said coupler butt.

3. A yoke having a hooded forward end constructed to permit insertion therein of a coupler butt, said hooded end being formed 105 with an engaging lip and an aperture in the horizontal wall thereof opposite said lip, a locking member attached to said yoke insertible and removable upwardly through 110 said aperture, said locking member being provided with means coacting with said lip to prevent removal of a coupler butt from said yoke, said locking member being further provided with a bearing surface for 115 said coupler butt, said surface being substantially in the same plane with the bearing surface of one arm of said yoke.

4. A yoke having a hooded forward end constructed to permit insertion therein of a coupler butt, said hooded end being formed 120 with an engaging lip and an aperture, a locking member attached to said yoke insertible and removable through said aperture, said locking member being provided with means coacting with said lip to prevent removal of a coupler butt from 125 said yoke, said locking member being further provided with a bearing surface for said coupler butt, said surface being substantially in the same plane with the bearing 130

surface of one arm of said yoke and terminating at a distance from the surface of said yoke arm less than the length of said coupler butt.

5. A yoke having parallel arms and provided with a hooded forward end integrally connecting said arms, said hooded end being adapted to receive a shouldered draw bar butt therewithin, said yoke being provided with means arranged to engage the upper shoulder of a draw-bar butt, and devices, coöperable with the lower shoulder of a draw-bar butt, for detachably locking the yoke to a draw-bar, said devices including a shouldered block removable downwardly through an opening in the bottom of the hood, and a horizontal key, said key being insertible from the rear of the hood

and adapted to support said block in position. 20

6. A yoke having a hooded forward end for receiving a shouldered coupler butt, the floor of the hood having an opening, and a block insertible into the opening from below and projecting above the floor to engage a shoulder of the coupler butt. 25

7. A yoke having a hooded forward end for receiving a shouldered coupler butt, the floor of the hood having an opening, a block insertible into the opening from below, and means for supporting the block in position to engage a shoulder of the coupler butt. 30

In testimony whereof, I have subscribed my name.

WILLIAM WRIGHT.
